CLUTCH OR LOCKING MECHANISM.

1,360,864.

Specification of Letters Patent. Patented Nov. 30, 1920.

Application filed June 16, 1919. Serial No. 304,545.

To all whom it may concern:

Be it known that we, CHARLES E. ARCHER and EDWARD C. HUMPHREYS, citizens of the United States of America, residing at Detroit, county of Wayne, State of Michigan, and Chicago, county of Cook, State of Illinois, respectively, have invented certain new and useful Improvements in Clutch or Locking Mechanism, of which the following is a specification, reference being had therein to the accompanying drawings.

In our allowed application Serial No. 238,468, filed June 6, 1918, for certain new and useful improvements in signal lamps, there is disclosed a signaling device or lamp having a universal movement and which may be easily and quickly manipulated with one hand for signaling purposes, the lamp being applicable to airplanes and other craft where it is necessary that a signal lamp be adjustable in all directions and capable of manipulation with one hand, so that the aviator may also attend to other duties while signaling. A novel locking device is also disclosed for maintaining the lamp in an adjusted position, and this application is directed to certain improvements in the locking mechanism.

The present invention aims to provide a simple and compact clutch and locking device for shafts or rotary members relative to a support and the locking device will be hereinafter considered and then claimed.

Reference will now be had to the drawing, wherein—

Figure 1 is a side elevation of a signal lamp, partly broken away and partly in longitudinal section, showing the lamp and its supporting yoke locked relative to a bearing;

Fig. 2 is a longitudinal sectional view of the locking device showing the same in position for simultaneously adjusting the lamp and its supporting yoke;

Fig. 3 is a similar view showing the locking device in position for adjusting the lamp independent of its supporting yoke;

Fig. 4 is a cross sectional view taken on the line IV—IV of Fig. 1, and

Fig. 5 is a similar view taken on the line V—V of Fig. 1.

In the drawing, the reference numeral 1 denotes a support and clamped or otherwise connected to said support is a tubular bearing 2 which has the outer end thereof flanged, as at 3 to abut a yoke head 4 and said yoke head is rotatably held at the outer-

end of the tubular bearing by an annular member 5 connected to the yoke head and cooperating therewith in providing an annular groove for the flange of the tubular bearing, so that the yoke head may be rotated relative to the axis of said bearing. The hollow yoke head 4 has diametrically opposed hollow or tubular yoke arms 6 supporting casings 7 having trunnions 8 for a lamp 9.

Mounted on the inner end of the tubular bearing 2 is the hub 10 of a stationary toothed member 11 which has its inner face flush with the inner end of the tubular bearing.

Journaled in the tubular bearing 2 is a yoke sleeve 12 supporting the yoke head 4 and the inner end of the yoke sleeve 12 has a yoke toothed member 13 mounted thereon against the stationary toothed member 11, and provided with a hub portion 14 which extends to the inner end of the yoke sleeve 12.

Journaled in the yoke sleeve 12 is a lamp shaft 15 which has the outer end thereof extending into the hollow yoke head 4 and provided with a mechanism, generally designated 16, for transmitting motion to the trunnions 8 of the lamp 9, so that said lamp may be adjusted in the yoke and independently thereof. The lamp 9 may also be adjusted in synchronism with the yoke, and on the inner end of the lamp shaft 15 is mounted the hub portion 17 of a lamp toothed member 18 which incloses the hub 14 of the toothed member 13 and abuts said toothed member, all of the toothed members being of the same diameter.

The manner of mounting the toothed members on their respective rotary bodies is best shown in Figs. 4 and 5, where it will be observed that the end of the yoke sleeve 12 has opposed facets or flat surfaces for the hub portion 14 of the toothed member 13, and the inner end of the lamp shaft 15 has similar facets or surfaces for the hub portion 17 of the toothed member 18. To prevent longitudinal displacement of these members a nut or cap 19 is mounted on the extreme inner end of the lamp shaft 15.

Slidably mounted on the hub portion 17 of the toothed member 18 is the inner reduced end 20 of a lock housing 21, said lock housing having a stationary toothed wall 22 and a movable toothed wall 23, said movable toothed wall 23 being in the form of a ring or band loosely mounted in the outer end of

the housing 21 and retained therein by a flange or peened edge 24 of said housing. The toothed portions of the walls 22 and 23 longitudinally aline so as to be shifted into 5 and out of mesh or interlocking engagement with the toothed members 11, 13 and 18.

The inner reduced end 20 of the lock housing 21 has suitable hand grip members 25 and said housing has a spring pressed 10 detent 26, preferably in the form of a ball, adapted to engage in an annular groove 27 in the hub portion 17 of the toothed member 18, said groove and detent defining a neutral position of the locking device. The lock 15 housing is placed in position prior to placing the nut 19 on the end of the lamp shaft 15, and then said nut will coöperate with the lamp toothed member 18 in limiting the sliding movement of the lock housing relative to 20 the toothed members 11, 13, and 18.

As shown in Fig. 1, the locking device or the housing thereof is in a neutral position and it is impossible for the lamp or its supporting yoke to accidentally shift. Since 25 the toothed member 11 is stationary and meshes with the movable toothed wall 23 of the lock housing 21, and the toothed members 13 and 18 mesh with the movable and stationary toothed walls of the housing, it 30 is impossible to rotate the lock housing without longitudinally shifting the same, and the detent 26 engaging in the groove 27 will prevent accidental shifting of said lock housing.

The hand grips 25 permit of the lock housing being shifted longitudinally of the toothed members, and as shown in Fig. 2, the toothed wall 23 of the lock housing 21 is held stationary by the stationary toothed 40 member 11, but since the wall 23 is movable in the lock housing, said lock housing may be rotated and by reason of its interlocking engagement with the toothed members 13 and 18, a rotary movement may be imparted 45 to the yoke sleeve 12 and the lamp shaft 15, in either direction. It is therefore possible to adjust the yoke with the lamp remaining stationary therein, the yoke rotating about the yoke sleeve 12 as an axis.

As clearly shown in Fig. 2 the detent may 50 ride out of the groove 27 and the correct position of the lock housing will be defined by contacting with the toothed member 18. A reverse position is shown in Fig. 3 where 55 the lock housing has been pulled inwardly to place the movable toothed wall 23 in engagement with the stationary toothed member 11 and the yoke toothed member 13. The yoke toothed member 13 is therefore 60 locked relative to the stationary toothed member 11, but the lock housing may be rotated to impart movement to the lamp shaft 15 by reason of the housing being interlocked with the lamp toothed member 18.

From the foregoing, it will be observed

that we have devised and adjusting mechanism embodying rotatable concentric members held relative to a stationary member, and that the ends of said rotatable members are inclosed by a rotatable and reciprocable 70 selective element, including a ring, that permits of an operator using one hand to effect a desired adjustment of either concentric member.

We would have it understood that the 75 structural elements of our invention are susceptible to such changes as fall within the scope of the appended claims.

What we claim is:

1. The combination of a tubular bearing, 80 a rotatable sleeve in said bearing, a rotatable shaft in said sleeve, a stationary toothed member on said bearing, toothed members on said sleeve and shaft, and reciprocable means on all of said toothed members adapted for locking the sleeve and shaft toothed members against rotation and permit of said shaft toothed member being rotated independently of said sleeve toothed member.

2. The combination of a tubular bearing, 90 a rotatable sleeve in said bearing, a rotatable shaft in said sleeve, a stationary toothed member on said bearing, a toothed member on said sleeve, a toothed member on said shaft, and selective means of rotation for 95 said sleeve and shaft members so that said members may be rotated in unison and said shaft member independently of said sleeve member.

3. The combination set forth in claim 2, 100 wherein the selective means is movable on the toothed member of said shaft.

4. The combination set forth in claim 2, 105 wherein said selective means is reciprocable, and additional means on said shaft coöperating with the toothed member on said shaft in limiting the reciprocable movement of said selective means.

5. The combination of a tubular bearing, 110 a rotatable sleeve in said bearing, a rotatable shaft in said sleeve, a stationary toothed member on said bearing, a toothed member on said sleeve, a toothed member on said shaft, and rotatable and reciprocable selective means adapted for engagement with all 115 of said toothed members, so that in one position said sleeve and shaft are locked relative to said bearing; in another position said sleeve and shaft are held for adjustment in unison, and in another position said bearing and sleeve held so that said shaft may be adjusted.

6. The combination of concentric rotatable members, rotatable and reciprocable selective means inclosing ends of said concentric rotatable members and adapted by adjustment to effect independent movement of said members, and means associated with said selective means and adapted for locking 125 said members.

7. The combination of concentric rotatable members, a stationary member, an adjustable member on the ends of said stationary and rotatable members, and a ring in said adjustable member adapted to coöperate with said stationary and adjustable members in locking said rotatable members, and coöperate with said stationary member and one of said rotatable members in locking only one of said rotatable members.

8. The combination set forth in claim 7,

wherein said adjustable member and ring are reciprocable relative to said rotatable members.

In testimony whereof we affix our signatures in presence of two witnesses.

CHARLES E. ARCHER.

EDWARD C. HUMPHREYS.
